PHILIP A. BROWN, OF INDIANAPOLIS, INDIANA.

Letters Patent No. 85,362, dated December 29, 1868.

IMPROVED MOULD FOR FORMING ROOFING-TILES.

The Schedule referred to in these Letters Patent and making part of the same.

To all whom it may concern:

Be it known that I, PHILIP A. BROWN, of Indianapolis, in the county of Marion, and State of Indiana, have made and invented a new and useful Improvement in Moulds for Forming Roofing-Tiles; and I do hereby declare that the following is a full, clear, and exact description thereof, which will enable others skilled in the art to make and use the same, reference being had to the accompanying drawings, forming part of this specification.

The nature of my invention relates to improvements in moulds for making roofing-tiles; and

It consists in the construction of the moulds, as will be hereinafter more fully described.

Figure 1 represents a plan view of the lower part of a mould for forming the sections.

Figure 2 represents one half of the top part of the same.

Figure 3, the other half of the top.

Figure 4, a sectional elevation of a machine for pressing the moulds together, with the moulds therein.

A represents a mould-box, provided with different compartments, in which the several sections are formed, together with the parts B and B'; the part A giving the configuration to the bottom and edges of the sections and the top and edges of the caps, and the parts B and B' giving the configurations to the tops of the sections and the bottoms of the caps.

The sections for the lower tier, beginning at the eaves, as shown in red at C, Figure 5, are formed in the mould a b, the widened and depressed end b' of the top former b, provided with the pins b'', forming the expanded elevation, and the nail-holes in the upper end of the section C, and the recesses b' in the lower end of the top former, form the projections on the lower end of the section C.

The mould a', provided with the narrowed elevation

b', together with the top former, which is similar to the top former b, with the exception of the recesses b' forming the intermediate sections.

The mould a'', together with the top former a'', is for making the top or ridge sections, the bottom ends being similar to the other intermediate sections, but the upper ends differing from the others, in the respect that the elevated portion is not widened.

The projections e e, in the top former B', form the depressions e' e'' for the projecting lugs, on the lower ends of the cap-pieces.

Ribs f f are formed in the sides of the lower part A of the mould, to form grooves in the edges of the sections for the passage of the nails for holding on the caps. The nail-holes of all the parts are made in the upper ends.

In the use of the press which I have shown, several sets of moulds may be operated on at the same time, one being placed on the top of another.

H represents a stationary frame, provided with a movable frame, I, and a stationary table, K, on which the moulds may be placed under the sliding frame I, which is pressed down upon the moulds by the levers L and L'.

Having thus described my invention,

I claim as new, and desire to secure by Letters Patent—

The arrangement of a series of moulds formed in the parts A, B, and B', for forming roofing-tiles and caps, such as herein shown, all constructed in the manner as and for the purpose specified.

PHILIP A. BROWN.
